UNITED STATES PATENT OFFICE

2,638,053

LIQUID FUEL INJECTION PUMP FOR
INTERNAL-COMBUSTION ENGINESWilfrid Edward Walter Nicolls, Pinner, England,
assignor to C. A. V. Limited, London, EnglandApplication January 9, 1950, Serial No. 137,593
In Great Britain January 13, 1949

2 Claims. (Cl. 103—41)

1

This invention relates to a liquid fuel injection pump having one or more reciprocatory plungers for injecting liquid fuel into the cylinder or cylinders of an internal combustion engine, the pump being of the kind in which the fuel inlet port or each such port is controlled by the associated plunger.

For some purposes, it is desired to be able to advance the instant at which the fuel is injected into the engine with increasing engine speed, and the object of the present invention is to enable this requirement to be met in a simpler manner than heretofore.

In the accompanying drawings:

Figure 1 is a sectional elevation illustrating a pump embodying the invention, and

Figure 2 is a cross section of the pump barrel on the line 2—2, Figure 1.

Referring to the drawings, the greater part of the pump there shown is of known construction. It comprises a pump barrel *a* (or a plurality of such barrels arranged parallel with each other), the barrel or barrels being secured within a hollow body part *b*. The reciprocatory plunger *c* is actuated in one direction through a slipper *d* by a rotary cam *e* and in the opposite direction by a spring *f*. For regulating the output of the pump, the plunger *c* has formed on it in known manner a spill groove *g*, the position of which in relation to the inlet port or ports *h* in the bore can be varied by angular movement of the plunger about its axis. This movement is effected by the action of a governor or other controlling means on a slidable rack *i* engaging a pinion *j* on a sleeve *m* which is connected to the plunger by a cross pin *n*.

In the pump above described the barrel is provided with two main ports *h* which open into an annular feed chamber *o* in the body part, this chamber being supplied with fuel oil by a pipe connected to an inlet *p*.

According to the present invention there is provided in the barrel a small supplementary inlet port *q*. This latter is so disposed as shown relatively to the main ports that it can be closed by the plunger after the latter has moved through a distance of from 0.25—0.5 mm., beyond the position in which it has closed the main ports. Also the cross section of the supplementary port is such that it can serve as a throttle for suitably restricting the rate of flow of liquid therethrough.

The arrangement is such that when the pump is working slowly, discharge through the spring

2

loaded delivery valve *r* and hence at the injection nozzle in the engine will not commence until after both ports *h*, *q* have been closed. But with increasing speed of the pump, the instant of discharge will be progressively advanced owing to the resistance of the supplementary port *q* to flow through it from the pump barrel.

By the expedient above described the automatic advancing of the instant of fuel injection with increasing engine speed can be effected in a very simple and satisfactory manner.

The invention is not, however, restricted to the example described, as the supplementary port may be provided in other ways. Thus, it may consist of a small notch formed in the upper part of the main port or each such port. Further it will be understood that whereas in the foregoing only one pump barrel and plunger, with their associated parts, have been described, each barrel in a multi-plunger pump is provided in like manner with a supplementary port.

Having thus described my invention what I claim as new and desire to secure by Letters Patent is:

1. A liquid fuel pump having in combination a hollow body part provided with a fuel inlet passage, a barrel arranged in the hollow body part and provided with at least one main fuel inlet port and a restricted supplementary inlet port, both ports being in communication with the fuel inlet passage, and a plunger slidably in the barrel for closing both ports and discharging liquid fuel from the barrel, the restricted supplementary inlet port being disposed in relation to the main inlet port so that it is closed by the plunger shortly after the main port has been closed thereby, and said supplementary inlet port being dimensioned so that when the pump speed is high only a limited amount of fuel can escape therethrough whereas at lower pump speeds a greater amount of fuel can escape through said port.
2. A liquid fuel pump as claimed in claim 1, in which the said supplementary inlet port is spaced from the main port.

WILFRID EDWARD WALTER NICOLLS.
